200,206

CABINET OR SIMILAR ARTICLE

George A. Arkwright, 6708 New Hope Drive,
Springfield, Va.

Filed Oct. 31, 1962, Ser. No. 72,323

Term of patent 14 years

(Cl. D33—19)

FIGURE 1 shows a front elevational view of my cabinet.

FIGURE 2 is a top view thereof.

FIGURE 3 is a side elevational view of my cabinet as shown in FIGURE 1.

FIGURE 4 is a sectional view taken along the lines 4—4 in FIGURE 1.

FIGURE 5 is a side section taken along the lines 5—5 of FIGURE 1, and omitting the shelves in the interior of the cabinet.

Both sides of the cabinet are identical and the back is plain and unornamented.

I claim:

The ornamental design for a cabinet or similar article, substantially as shown and described.

References Cited by the Examiner

UNITED STATES PATENTS

D. 99,607	5/36 Scurlock -----	D33—14
2,165,930	7/39 Levine et al.
2,521,547	9/50 Simon.

OTHER REFERENCES

Furniture Age, May 1937, page 4, upper left center.
Sears, Roebuck and Co. Catalog, F & W 1942—43, page
771A, Console bookcase at right center.

EDWIN H. HUNTER, Primary Examiner.